UNITED STATES PATENT OFFICE

JOSEPH C. BRUNO, OF BUFFALO, NEW YORK, ASSIGNOR, BY MESNE ASSIGNMENTS, TO THE VOL-U-METER COMPANY, INC., OF BUFFALO, NEW YORK, A CORPORATION OF NEW YORK

CAN-FILLING MACHINE

Application filed February 18, 1925. Serial No. 10,096.

My invention relates in general to can filling machines and particularly to the type of machine in which the flow of liquid is interrupted when the predetermined amount has been drawn from the machine.

One of the objects of my invention has been to provide a machine of this type in which fluid coming from the machine shall be under constant head.

10 Another object has been to provide a device having parts so constructed and arranged that the device may be very easily cleaned.

Moreover, my device is of such a nature 15 that there is no spatter or after-flow of the fluid being handled.

Furthermore, my device is simple in its construction, and all the parts may be quickly and readily disassembled for purposes of cleaning.

The above objects and advantages have been accomplished by the device shown in the accompanying drawings, of which:

Fig. 1 is a front elevation, partly in 25 section.

Fig. 2 is a plan view of the device, slightly enlarged.

Fig. 3 is an enlarged fragmentary portion 30 of the tripping mechanism of the device.

Fig. 4 is an enlarged fragmentary, sectional view of the inlet valve.

The device comprises a base 10, which is provided with three leveling screws 11, each passing through the base and preferably 35 having a lock nut 12 for setting the screw in its adjusted position. Carried by the base 10 is a screw-threaded standard 13, by which the parts of my device are supported on the base in an adjustable manner.

40 Arranged near the upper end of the standard 13 is the reservoir 14 of my device. This reservoir is secured to and supported by a reservoir bracket 15, one end of which passes over the standard 13 and which is 45 adjustably held in place on the standard by means of a hand wheel 16, screw-threaded to the standard. By this means, the reservoir may be raised and lowered to accommodate various sized receptacles or cans. A 50 cover 17 is preferably provided for the

reservoir, whereby foreign matter will be prevented from getting into the reservoir, as well as preventing the vaporization of the fluids being handled.

Arranged at one side of the reservoir 14 is 55 the fluid control of my device, which comprises an inlet valve 19, pivotally hung in an inlet valve yoke 20, which is carried by a valve-seat nipple 21. The valve-seat nipple is screw-threaded to the reservoir 14. 60 The valve yoke 20 is secured in position on the nipple preferably by means of the bolt 18 and it is provided with two forwardly extending and interspaced ears 22, each of which has an upwardly extending lug 23 at 65 its forward end. The yoke is so positioned that these lugs are arranged above the valve 19. The valve is provided with an upwardly extending ear 24, which passes between the lugs 22 of the yoke and a pin 25, passing 70 through the ear and engaging with the upper surfaces of the lugs 22, serves to pivotally support the valve 19. The surface of the valve-seat nipple 21 is finished off smoothly so that the valve may efficiently 75 seat thereon. If desired, a flexible washer 26 may be provided on the valve 19 to insure its proper seating. The yoke 20 is provided at its lower side with a forwardly extending arm 27, to which is pivotally attached an inlet valve lever 28. This valve lever is mounted upon a pin 29, which is passed through the lever and the arm 27. This pin extends outwardly some distance 80 so as to provide a handle, and a cotter pin 30 passes through the pin 29 and into a lug 31, carried by the arm 27, whereby the pin 29 is held in position. This structure permits quick and easy disassembling of the device for cleaning.

85 The inlet valve lever 28 is preferably provided with an upstanding, slotted arm 32 to which the float arm 33 is attached. A wing nut 34 serves to adjustably clamp the float arm to the arm 32 of the valve lever, whereby the float 34, carried by the arm 33, may be raised or lowered with respect to the valve lever. By this means the level or head of fluid within the reservoir may be altered to suit the viscosity 90 of the fluid being handled. The float also 95 100

may thus be maintained in its most efficient position with respect to the surface of the liquid.

A flexible inlet connection 35 is attached to the valve-seat nipple 21 by means of a union coupling 36. The inlet connection comprises two members 37 and 38, which are joined at 39 with a liquid-tight joint and which are held together by means of a clamp 40. It will be seen that this connection may be moved to any angle suitable for attachment to the supply of liquid, and at the same time it is one which may be quickly and easily disassembled, thus permitting thorough and easy cleaning.

The bottom 41 of the reservoir is preferably sloped and arranged in one corner of the low side thereof, is an outlet opening 42, which is preferably interiorly screw-threaded. Fitted into this opening is an outlet valve housing 43, in which is mounted an outlet valve 44. This valve is loosely attached to the rod 45 of the closing weight 46, preferably by means of the cotter pin 47. Arranged in the upper end of the reservoir is a valve arm 48 which has its outer end in hooked engagement with the closing weight 46. The other end of the arm is mounted upon an operating shaft 49, preferably by means of a screw 50, whose end 51 fits into a hole formed in the shaft 49. By these means the valve arm may be easily and quickly removed from the shaft for cleaning and may always be assembled in the same position with respect to the shaft 49. The valve 44 and closing weight 46 may also be conveniently removed for cleaning. The operating shaft 49 is rotatably mounted within the bearing 52 and is prevented from moving endwise within this bearing by any suitable means, but preferably by a screw 53 which passes through the bearing and into an annular groove formed in the shaft. This is a common and well known means of preventing endwise motion of a shaft and, therefore, is not shown in the drawings.

Mounted upon the outer end of the operating shaft 49 is an outlet valve lever 55. This lever is held in place upon the shaft by means of a bolt 56, which passes through a groove 59 formed in the periphery of the shaft, whereby the arm may be rotated by loosening the screw without danger of the same sliding endwise upon or becoming detached from the shaft. Carried by this valve lever is an operating handle 57 which is secured to the lever and has its forward end bent downwardly and within easy reach of the operator. An adjustable counter-weight 58 is carried by the rear end of the handle.

Rigidly attached to the front side of the reservoir is a bracket 60, which has pivotally attached to it a trip lever 61. This lever

projects forwardly within easy reach of the operator where it may be actuated manually if desired. A spring pressed plunger 62 is carried by the trip lever and has its lower end in engagement with a lug 63, carried by the bracket 60. The upper end of the plunger is provided with a head 64, which is mounted in a cylinder 65. A spring 66 is arranged within the cylinder and bears on top of the head 64. A screw 67 closes the upper end of the cylinder. The tendency of this spring pressed plunger is to normally keep the latch arm in a fixed position and up against an adjustable stop screw 68, which is carried by the bracket 60. Another stop screw 69 is carried by the bracket 60 and serves to limit the movement of the outlet valve lever 55.

Carried on the inner end of the trip lever 61 is a latch plate 70. A latch plate 71 is carried by the valve lever 55. The two latch plates 70 and 71 are beveled so that when the valve lever 55 is moved to its open position, the two knife edges on the plates will engage with each other against the tension of the spring pressed plunger 62, and be held in such engaged position by this plunger, as clearly shown in Fig. 3. A trip cam 75, having a cam face 76, is pivotally carried by the bracket 60. This cam is provided with a counter-weight 77, which balances the weight of the horizontal trip rod 78. The trip rod is rigidly attached to the trip cam 75 and extends downwardly and rearwardly, as shown in the drawings, where it may be engaged by the balance, to be hereinafter described.

I preferably provide my device with a gage 73 which is secured to the side of the reservoir 14 and which has a pointer 74 carried by the valve lever 55 and preferably arranged under the operating handle 57. By means of this gage the amount of opening of the outlet valve 44 may be gaged.

Arranged beneath the reservoir 14 is a balance 80 of any well known type. This balance is carried by a supporting bracket 81 which has one of its ends disposed about the standard 13 and is held in its adjusted position by means of the hand wheel 82. The balance is provided with the usual balance beam 83 which carries a sliding weight 84 on its graduated end 85 and a can platform 86 on its opposite end. The end 85 of the beam carries a vertical trip rod 87 which engages the outwardly extending end of the horizontal trip rod 78, and which raises the horizontal trip rod when the beam is tipped by the weight of the filled receptacle. The can platform 86 is provided preferably at its central portion with a drip opening 88, extending from which is an inclined trough 89, whereby any drips coming from the valve when the receptacle is removed from the platform will be caught in 130

the drip opening and conducted away from the platform by the trough 89 and thereby prevented from coming in contact with the bottom of the next receptacle which is placed upon the platform.

When it is desired to put my device into use, the flexible inlet connection 35 is connected with the source of supply of fluid and the same is allowed to flow through the coupling and valve-seat nipple 21 and into the reservoir 14, past the valve 19. The outlet valve 44 being closed, the liquid will be collected in the reservoir until it has been filled to the predetermined point, whereby the float 34 will have moved the inlet valve lever 28 to a position where it will bear against the valve 19 and hold it firmly against the valve-seat nipple 21, thus closing the inlet. A receptacle 90 is now placed upon the can platform 86, the sliding weight 84 having been moved on the balance beam to the proper position. The operating handle 57 is now raised which will raise the outlet valve 44 through the medium of the outlet valve lever 55 and rod 45. The operating handle will be moved up until the valve lever 55 engages the stop screw 69, the amount of opening having been previously determined by the gage 73. When the valve lever 55 strikes the stop screw 69, the latch plates 70 and 71 will have come into their engagement positions and will thus hold the outlet valve 44 in its open position. When the receptacle 90 has been filled to the predetermined point, the beam 83 will be balanced, and the vertical trip rod 87 will thus be moved upwardly. As the rod 87 moves, it engages the horizontal trip rod 78 and moves it, thus rotating the cam 75 about its pivotal point. The cam face 76 will thus be brought against the under surface of the inner end of the trip lever 61, thereby forcing it upwardly and depressing the outer end against the tension of the spring pressed plunger 62. This will serve to release the latch plate 70 from engagement with the latch plate 71, carried by the outlet valve lever 55 and thus allow the valve lever to move to the position shown in Fig. 1 by the force of gravity exerted by the closing weight 46, whereby the outlet valve 44 will be closed, thus shutting off further supply of liquid to the receptacle 90.

It will be understood that while the liquid is flowing through the outlet opening, in the valve casing 43, the level of the liquid in the reservoir 14 will be maintained constant because of the float.

From the foregoing, it will be clear that when the machine is to be cleaned, all of the parts which come in contact with or are submerged in the liquid being handled, may be easily and quickly removed from the receptacle, the interior of which, after their

removal, may be easily and thoroughly cleaned.

Obviously some modifications of the details herein shown and described may be made without departing from the spirit of my invention or the scope of the appended claims, and I do not, therefore, wish to be limited to the exact embodiment herein shown and described, the form shown being merely a preferred embodiment thereof.

Having thus described my invention, what I claim is:

1. A can filling machine comprising a reservoir, a fluid inlet therefor, a fluid outlet in the bottom of the reservoir, a valve in the reservoir outlet, an outlet valve lever connected to the outlet valve, a trip lever, a trip plate carried by the outlet valve lever, a trip plate carried by the trip lever, spring-pressed means for keeping said plates in engagement to maintain the outlet valve in open position, a trip cam engageable with the trip lever, and means for actuating the trip cam in accordance with the weight of the liquid flowing from the outlet valve to effect the closing of the outlet valve.

2. A can filling machine comprising a reservoir having an inlet and an outlet, a valve for the inlet, a valve in the reservoir outlet, an operating shaft passing through the reservoir above the normal liquid level, an outlet valve lever upon said shaft, and an operating arm connecting said lever and said outlet valve, a trip lever, trip plates carried by the outlet valve lever and trip lever, respectively, spring-pressed means for keeping said trip plates in engagement to maintain the outlet valve open, a trip cam engaging the trip lever, and means controlled by the weight of the liquid flowing from the outlet valve for actuating the trip cam to permit the closing of the outlet valve, and a weight within the reservoir attached to the outlet valve therein for closing said valve.

3. A can filling machine comprising a reservoir, an operating shaft passing through the reservoir at a point above the normal liquid level, an inlet valve, an outlet valve, a closing weight attached to the outlet valve, a valve arm connected at one end with the closing weight and having its other end mounted on the operating shaft, the outlet valve, closing weight and valve arm being enclosed within the reservoir, and means carried on the outside of the reservoir for controlling the operation of the outlet valve by and in accordance with the weight of the liquid flowing therefrom.

4. A can filling machine comprising a reservoir, a fluid inlet for the reservoir, a float mounted in the reservoir, means actuated by the float for controlling the fluid inlet, an outlet valve in the bottom of the reservoir, a closing weight within the reser-

voir attached to the outlet valve, a valve arm within the reservoir, and means for controlling the operation of the valve arm and outlet valve by and in accordance with the weight of the liquid flowing from the outlet valve.

5. A can filling machine comprising a reservoir, an operating shaft passing through the reservoir, an inlet valve, a float mounted in the reservoir, means actuated by the float for controlling the inlet valve, an outlet valve, a closing weight attached to the outlet valve, an outlet valve rod on the operating shaft, the outlet valve, closing weight and valve rod being enclosed within the reservoir, and means including an operating arm on the shaft outside of the reservoir for controlling the operation of the shaft and outlet valve by and in accordance with the weight of the liquid flowing from the outlet valve.

In testimony whereof, I have hereunto set my name.

JOSEPH C. BRUNO.
